BEER DISPENSER

Henry E. Frey, 26 Mayflower Court, Freeport, N.Y.

Filed Oct. 17, 1962, Ser. No. 72,148

Term of patent 14 years

(Cl. D2—3)

FIG.1.

FIG.2.

FIG.3.

The dominant features of my design reside in the full line portions of the drawing.

I claim:

The ornamental design for a beer dispenser, as shown and described.
